UNITED STATES PATENT OFFICE

2,507,099

CLOTH PLACING APPARATUS

Samuel Ganis, Evanston, Ill., assignor to Smoler Bros., Inc., Chicago, Ill., a corporation of Illinois

Application December 8, 1945, Serial No. 633,806

13 Claims. (Cl. 270—31)

1

This invention relates to cloth placing apparatus and is particularly useful in the placing or laying of cloth strips upon a table or other surface with the strips accurately aligned along one edge thereof. The invention will be found to have a number of other uses.

An object of the invention is to provide mechanism for laying cloth strips upon a cloth receiving surface with at least one edge of the cloth lying in a straight longitudinal line. A further object is to provide means for placing or laying cloth in superposed strips upon a surface while maintaining the cloth strips along one edge thereof in vertically aligned relation. A further object is to provide apparatus for carrying and laying cloth together with means for rotating the carrying means to reverse the direction of placement when desired. Yet another object is to provide traveling means for carrying a roll of cloth and for guiding the delivery of cloth therefrom to a cloth receiving surface, while at the same time providing means for applying resistance to the rotation of the cloth roll. Other specific objects and advantages will appear as the specification proceeds.

The invention is illustrated, in preferred embodiments, by the accompanying drawings, in which—

Figure 1 is a broken front view in elevation of apparatus embodying my invention; Fig. 2, a broken side view in elevation of the structure shown in Fig. 1; Fig. 3, a broken detail perspective view of control apparatus engaging one edge of the cloth and employed for maintaining the edge in a straight longitudinal line upon the table; Fig. 4, a plan sectional view, the section being taken as indicated at line 4 of Fig. 2; Fig. 5, a detail sectional view, the section being taken as indicated at line 5 of Fig. 4; Fig. 6, a broken vertical sectional view of a modified form of support for suspending the cloth carrying means employed, and Fig. 7, an enlarged sectional detail view of limit switches shown in Fig. 3.

In the illustration given, A designates the top portion of a table or other cloth receiving surface; B represents a traveling crane or frame member carried by tracks upon the table A; and C, a cloth carrying carriage suspended from member B.

The structure A may be a table, floor, platform or any other suitable cloth receiving surface. The floor A is provided with an angle iron track 10 on one side and an angle iron track 11 on the other side. The angle iron track 11 is,

2

however, extended to a higher elevation and is provided at its top with teeth 12 providing a rack.

The traveling crane or frame member B may be of any suitable form or construction. In the illustration given best in Figs. 1 and 2, the frame member B is equipped on each side with a pair of standards 13 and 14 each of which carries wheels 15 at its lower end for engagement with the track members 10 or 11. The legs 13 and 14 are connected at their top by an integral crossbeam 16 which centrally carries standards 17 and 18. The central standards 17 and 18 are connected at their top by a bridge member 19 which is employed to support the carriage structure C.

The traveling carriage C is supported upon beam 19 of the member B for rotation when desired. As shown more clearly in Figs. 1 and 2, the member C is equipped with an angle iron frame member 20 in the shape of an inverted U. A large bolt 21 extends centrally through the top horizontal flange of the member 20 and is equipped with a head 22 which bears against such flange. The top portion of bolt 21 is threaded to receive the nuts 23 and 24. The bolt extends through a spacer member 25 resting upon the horizontal flange of the frame member 20, through the horizontal flange of the angle iron beam 19, through the block 26 resting upon the horizontal flange of the member 19, through the cap plate 27 and washer 28. Ball detents 29 urged by springs 30 may be employed for engaging recesses in the spacer member 25, which is welded to the member 20 and thus yieldably lock the member 20 in either one of its two extreme positions. Antifriction bearings 31 may be employed as illustrated.

The angle iron member 20 is provided with a plate 32 welded to one side of the member 20, as shown best in Fig. 4, and the plate 32 is provided with downwardly-extending notches 33 adapted to receive the shaft 34 of roll 35. The bolt 21 extends through plate 32 which, in effect, provides an extension of the horizontal flange of the frame member 20. Fixed to one end of the shaft 34 is a brake wheel 36 adapted to be engaged by a shoe 37 of the solenoid operated plunger 38. The plunger and solenoid are positioned to give the desired amount of braking pressure upon the roll shaft 34. Mounted in the lower portion of the flange portion 32 of the frame member 20 is the shaft 39 of the idler roller 40. Also mounted within the lower portion of the member 32 is the driven shaft 41 which carries the driven roller 42. The shaft 41 carries at each of its outer ends

gear member 43 which meshes with a large driving gear 44.

The driving gear 44 may be driven by any suitable means. In the illustration given, the driving gear 44 meshes on its outer side with the rack 12 for driving the structure B and meshes at the same time on its inner side with the driven gear 43 fixed to shaft 41.

The motor employed for driving gear 44 is carried by the member B on one side thereof. As shown more clearly in Fig. 2, the legs 13 and 14 of B are connected on one side by the crossbeams 45 and the motor structure 46 is supported thereon. The motor drives through reduction gears, not shown but housed within the structure 47, the large gear 44.

Mounted upon the shaft 41, as shown more clearly in Figs. 4 and 5, is a large plate 48 which provides a bearing at its lower end for a driven shaft 49. The shaft 49 carries the feed roller 50. A second plate 51 also receives the shaft 49 and carries the shaft 52 of an idler roller 53.

Any suitable means may be employed for adjusting the position of the idler roller 53 so as to cause it to maintain the cloth against the feed roller 50. In the illustration given, the plate 51 is free to pivot about shaft 49 and means are provided for maintaining the plate 51 at any desired adjusted angle. A link member 54 is connected by pin 55 to one end of the plate 51 and a shaft 56, which is fixed to plate 32, extends through an arcuate slot 57 of plate 48. The link 54 is clamped rigidly against plate 48 by the nut member 58 which engages the threaded end of shaft 56. By this means, the plate 51 may be swung to any desired angle upon the loosening of nut 58 and then clamped rigidly in position upon the tightening of nut 58 so as to secure the member 54 firmly in position. Clamping collars 59 and 60 are provided between the nut 58 and the members 48 and 54.

In order to drive the shaft 49, a pulley 61 is fixed to shaft 49 and shaft 41 is provided with a similar pulley 62. The two pulleys are connected by belt 63.

In the structure shown, the shaft 49 of driving roller 50 is mounted not only for rotation but for endwise movement, and the purpose of the endwise movement is to provide a control which will cause the cloth being fed to be laid always along a true or straight longitudinal line. In order to effect longitudinal movement of shaft 49, I provide each end of the shaft with a fine threaded portion 64 and 65, one of the threaded sections being a left-handed thread and the other being a right-handed thread. Secured upon the member 48 directly above the threaded portion 64 and 65 is a bracket 66 securing a solenoid 67. A pin 68 carried by the solenoid and which normally rests above the threaded portion 65 is adapted to be moved downwardly upon actuation of the solenoid to engage the fine threading of shaft 49, thus providing a fixed abutment which will cause the shaft 49 to move longitudinally in one direction. The pin 68 engaging the threaded portion 65 will cause the shaft 49 to move in one direction while the pin 68 engaging the threaded portion 64 will cause the shaft 49 to move in the opposite direction. The rotation of the shaft 49 causes the threaded portion of the shaft contacted by either of the pins to function as a cam and thus produce longitudinal movement of the shaft.

To control the solenoids 67, any suitable apparatus may be employed which will engage the

edge of the cloth and make the desired contacts when the cloth moves away from its proper line. In the illustration given, I provide a pair of limit switches 69 and 70, as shown in general detail in Fig. 3 and in greater detail in Fig. 7. Each of the switches is equipped with inwardly-extending contact plungers 71 and 72. The plungers engage a blade 73 pivotally mounted at 74. The plungers 72 and 71 are urged inwardly by means of the springs 73a, one of the springs being slightly stronger than the other so that the blade 73 is urged toward the cloth and such excess pressure being counterbalanced by the edge of the cloth. The blade is illustrated in Fig. 7 as lying in the position where it engages the cloth and the pressure of the cloth counterbalances the excess spring pressure on one side of the blade. This pressure is normally counterbalanced by the edge 75 of the cloth. If the cloth should swing inwardly, the bias of the member 73 causes it to follow the cloth and the limit switch 69 is actuated to set in operation one of the solenoids. The solenoid actuated brings its point 68 into engagement with one of the threaded portions on shaft 49 and causes the shaft to move instantly a slight distance from the left, thus bringing the edge of the cloth against the member 72. The switch 69 is thus again disconnected and movement of shaft 49 ceases. Should the edge 75 of the cloth move outwardly, the blade 73 is moved against plunger 72 and the switch 70 closes the circuit in which the other solenoid is placed and the point 68 of that solenoid engages the opposite threaded end of member 49 to shift it in the opposite direction. As the blade 73 returns to its central position, switch 70 is opened and the longitudinal movement of shaft 49 ceases.

The bracket member 76, as shown more clearly in Fig. 1, is employed to support the limit switches 69 and 70 and the blade 73 is pivotally mounted thereon.

As shown more clearly in Fig. 2, a plurality of members B may be employed for movement upon the single track and upon the rack member 12 for carrying successive rolls of cloth so that upon a single reciprocation of the device B across the table A, a plurality of strips of cloth may be laid upon the table, as indicated best in Fig. 1 and by the numerals 77, 78, 79, 80 and 81.

In the operation of the apparatus, a roll of cloth 36 is placed upon the free end of the shaft 34 and the free end of the shaft is swung into the notch 33, as illustrated in Fig. 1. The cloth 55 77 then passes downwardly between the idler roller 40 and the driven roller 42 and thence downwardly over the driven roller 50 and under the idler roller 53. The cloth strip 77 is then caused to lie upon the table A or as the topmost 60 layer of the strips upon table A. If the cloth strip 77 is not pressed with sufficient firmness against the feed roller 50, the nut 58 may be adjusted to swing the plate 51 to the desired angle and then the nut 58 may be secured in position to maintain the parts as so adjusted. The motor 46 drives through the reduction gears housed in structure 47 the large or double gear 44, so that the entire structure B travels upon the rack 12. Simultaneously, the inner portion 70 of gear 44 meshes with the driven gear 43 and thus drives the feed roll 42. Further, by means of belt 63, the shaft 49 is likewise driven and the feed roller 50, with its idler roller 53 causes the cloth to lie evenly upon the layers of cloth 75 resting upon table A.

It is of the utmost importance that the layers of cloth deposited upon table A be vertically aligned at least along one edge. If a large number of layers of cloth are thus accurately aligned along one edge, the cutter can accurately form the desired patterns starting with the aligned edges. In order to obtain such alignment, the limit switches 69 and 70, together with the interposed blade 73 follow each slight variation of the cloth edge 75 and through the actuation of the solenoid 67 cause the edge 75 to be brought back quickly to the desired line. If the cloth edge moves in one direction, one of the switches is actuated to cause the solenoid connected therewith to move its point 68 into engagement with a threaded end of shaft 49, thus moving the roll 50 edgewise and bringing the cloth edge back to its central position. If the cloth edge moves in the opposite direction, the other switch is closed so as to cause the solenoid in circuit therewith to bring its point 68 into engagement with the threaded end of shaft 49 to move roll 50 in the opposite direction. By this means, the edge 75 is maintained along a straight longitudinal line.

At the end of the travel of member B, it may be desired to feed the cloth back along the same line and to accomplish this, the carriage C is simply rotated upon the swivel bolt 21 so as to disengage the gear 43 on one side of the carriage and to bring the gear 43 on the opposite side thereof into engagement with the large gear 44. Since the gears are spaced to one side of the large gear 44, it will be noted that the rotation of the carriage C causes the gears 43 to mesh evenly with gear 44 and on opposite sides thereof depending upon the rotation of member C. Thus gear 44 will drive either of the gears 43 and thus bring about a feeding operation which is the same irrespective of the direction of movement of the member B.

The roll 35 is provided with solenoid means for braking the shaft 34 so that the feed will not be too great or too little.

If desired, means may be provided for stopping the motor whenever the cloth strip ends, tears, or ceases to exert any pressure upon the member 13. In this instance, when the edge 75 no longer is present, the member 13 swings toward the limit switch 69 and this causes the shaft 49 to be moved to the left where it engages the contact arm 87 and brings it into engagement with contact 87 in the motor circuit. The contact 87 leads to any suitable solenoid or relay which breaks the circuit in which motor 46 is connected. If desired, another spring arm 88 may be employed on the opposite side to make a connection with the contact 89, likewise leading to a solenoid for breaking the motor circuit. Thus, movement of the shaft 49 to either extreme position will result in stopping the motor. Thus when the edge of the cloth is entirely missing, the engagement of one of the pins with the threaded portion of shaft 49 causes the shaft to move laterally to one extreme of its movement so as to engage the contact 87 or 88 and thereby shut off the flow of current to the machine.

While the cloth herein has been described in reference to a roll 35, it will be understood that, if desired, the cloth may be served in folded packs and any suitable container may be provided for supporting the cloth thus folded, so that it may be fed through the rollers as heretofore described. It will be obvious that modifications in the structure may be readily made to provide for the serving of cloth folded in different arrangements.

In the use of the term "cloth" herein and in the appended claims, I intend to include all flexible material, whether formed of cotton, wool or other material commonly used in fabrics or whether formed of mineral, plastic or other material capable of being handled herein, and I desire, therefore, that the term "cloth" be considered in this broad sense.

While in the illustration given, I have shown the traveling member supported upon tracks, it will be understood that the support may be accomplished in a variety of ways. In the modification shown in Fig. 6, I provide an I-beam 32 which is suspended from an overhead beam (not shown) and the frame member B¹ has suspension members 33 and 34 equipped with wheels 35 which engage the lower flanges of the I-beam. The carriage member C¹ is supported by a swivel bolt 36 upon the member B¹.

While in the foregoing description, I have set forth the structure in considerable detail as illustrating one mode of employing the invention, it will be understood that such details may be modified widely by those skilled in the art without departing from the spirit of my invention.

I claim:

1. In cloth placing apparatus, a cloth receiving surface, means for feeding a roll of cloth above said surface, a roller mounted for rotational and endwise movement and adapted to feed cloth from said cloth feeding means onto said surface, means for pressing the cloth against said roller, means for moving said roller in an endwise direction, and control means engaging one edge of the cloth being placed and actuating said roller moving means to maintain said edge on a predetermined line along said surface, said roller moving means comprising a solenoid operated member engaging a threaded end of said roller.

2. In cloth placing apparatus, a cloth receiving surface, means for moving a roll of cloth above said surface, a roller mounted for rotational and endwise movement and adapted to feed cloth from said roll onto said surface, means for pressing the cloth against said roller, means for moving said roller in an endwise direction, and control means engaging one edge of the cloth being placed and actuating said roller moving means to maintain said edge on a predetermined line along said surface, said control means comprising microswitch means equipped with a member following the edge of the cloth.

3. In cloth placing apparatus, a cloth receiving surface, means for moving a roll of cloth above said surface, a roller mounted for rotational and endwise movement and adapted to feed cloth from said roll onto said surface, means for pressing the cloth against said roller, means for moving said roller in an endwise direction, and control means engaging one edge of the cloth being placed and actuating said roller moving means to maintain said edge on a predetermined line along said surface, said control means comprising limit switch members equipped with means engaging one edge of the cloth and said roller moving means comprising solenoid operated members adapted to engage threaded ends of said roller.

4. In cloth laying apparatus, a cloth receiving surface, means for supporting a roll of cloth above said surface, means for moving said cloth supporting means along said surface, a roller mounted for rotational and endwise movement and adapted to feed cloth from said roll onto said surface, means for pressing the cloth against said

roller, and means engaging one edge of said cloth and responsive thereto for moving said roller in an endwise direction to maintain an edge of said cloth along a predetermined longitudinal line.

5. In cloth laying apparatus, means for moving a roll of cloth above a cloth receiving surface, a roller for feeding cloth from said roll upon said surface, said roller being mounted for rotation and for movement transversely of said surface, electrically operated means for moving said roller transversely of said surface and in either direction, and means engaging an edge of the cloth and responsive to pressure by said edge for controlling said electrically operated means and thereby maintaining said cloth in a substantially straight longitudinal line.

6. In cloth laying apparatus, means for rotatably supporting a roll of cloth, means for moving said last mentioned means above a cloth receiving surface, means for applying resistance to the rotation of said roll of cloth, roller means for feeding cloth from said roll upon said surface, said roller being mounted for rotation and endwise movement, and control means engaging an edge of said cloth for actuating said roller in an endwise direction so that said cloth is fed with one edge thereof lying in a straight longitudinal line along said surface.

7. In cloth laying apparatus, means for supporting a roll of cloth above a cloth receiving surface, track means on said surface, a traveling frame member mounted for self-propelling movement upon said track and supporting said first mentioned means, roller means for feeding cloth from said roll as it is propelled across said surface so that said cloth lies upon said surface, said roller being mounted for rotation in endwise movement and control means engaging an edge of said cloth for actuating said feeding means so that said cloth is fed with one edge thereof lying in a straight longitudinal line along said surface.

8. In cloth laying apparatus, a cloth receiving surface, a traveling member, means for supporting said traveling member for movement across said surface, a carriage suspended from said traveling member, and adapted to carry a roll of cloth, roller means for feeding cloth from said carriage upon said surface, said roller being mounted for rotation and endwise movement, and electric means engaging an edge of said cloth for controlling the endwise movement of said roller to bring one edge of the cloth along a predetermined straight line.

9. In cloth placing apparatus, a traveling frame member mounted for movement over a cloth receiving surface, a motor carried by said frame, a gear driven by said motor, a carriage member pivotally mounted on said frame said carriage being adapted to support a roll of cloth, and a driven roller extending through said carriage and equipped with a gear on either end, said gears being adapted to engage said motor driven gear at opposite sides thereof when said carriage is swung to its two extremes of movement, said roller being adapted to be rotated to feed the cloth from the roll.

10. In cloth placing apparatus, a traveling frame member mounted for longitudinal movement across a cloth receiving surface, a motor carried by said frame, a rack carried by said cloth

receiving surface, a gear driven by said motor and engaging said rack, said gear extending beyond said rack, a carriage member supported on said frame member, said carriage being adapted to support a roll of cloth, and a driven roller carried by said carriage member, said roller being equipped with a gear meshing with said first mentioned gear, said roller being adapted to be rotated to feed the cloth from the roll.

11. In cloth placing apparatus, a cloth receiving surface, a track thereon, a rack also carried by said cloth receiving surface, a traveling frame member mounted on said track, a motor carried by said frame member, a gear driven by said motor and engaging said rack, said gear also extending beyond said rack, a carriage member pivotally supported on said frame member, a driven roller extending through said carriage and having a gear at either end thereof, said carriage being adapted to support a roll of cloth, each of said gears being adapted to mesh with a portion of said first mentioned gear when said carriage is moved to either extreme of its rotation to reverse its position, and means including said driven roller for feeding cloth from said roll onto said surface whereby upon the reversing of said carriage said driven roller means will feed said cloth in either direction.

12. In cloth placing apparatus, a cloth receiving surface, means for feeding cloth above said surface, a roller mounted for rotational and endwise movement above said surface and adapted to feed cloth from said cloth feeding means onto said surface, means for pressing the cloth against said roller, means for moving said roller in an endwise direction, and means actuated by said roller when moved to one extreme endwise position to stop said cloth feeding means.

13. In cloth placing apparatus, a cloth receiving surface, means for moving a roll of cloth above said surface, a roller mounted for rotational and endwise movement and adapted to feed cloth from said roll onto said surface, means for pressing the cloth against said roller, means for moving said roller in an endwise direction, and control means including an element engaging an edge of said cloth and actuating said roller-moving means to maintain said edge on a predetermined line along said surface, and means cooperating with said last-mentioned means for stopping the rotation of said roller when the end of the cloth piece is reached.

SAMUEL GANIS.
